UNITED STATES PATENT OFFICE.

ELLIS W. SCARBOROUGH AND EDSON W. FLETCHER, OF SEARSPORT, MAINE.

WIRE-CONNECTING DEVICE.

1,255,233.

Specification of Letters Patent.

Patented Feb. 5, 1918.

Application filed May 31, 1916. Serial No. 100,813.

To all whom it may concern:

Be it known that we, ELLIS W. SCARBOROUGH and EDSON W. FLETCHER, citizens of the United States, residing at Searsport, in the county of Waldo and State of Maine, have invented certain new and useful Improvements in Wire-Connecting Devices, of which the following is a specification.

This invention relates to wire splicing or connecting devices, and has for its primary object to provide a simple and improved mechanism whereby wire ends may be securely, quickly, and easily connected.

A further object of the invention is to provide a device of this character which is of simplified and improved construction, which is composed of but few readily assembled parts, all so constructed and arranged as to preclude wear, breakage, or derangement of the same, which is positive in operation, and which will prove thoroughly efficient in attaining the ends for which it is designed.

A still further object of the invention is to provide a device of this character, which is capable of being quickly applied to the wire ends, and which is provided with improved means for locking the twisting element when the latter has been operated to give the wire ends the requisite number of twists or convolutions.

A still further object of the invention is to provide a twisting element to be used in connection with a wire clamping or holding device and wherein the convolutions or twists made in the wire by the twisting element operate upon the latter to automatically move the same away from the clamping means.

With these objects in view, together with others which will appear as the description proceeds, the invention resides in the novel formation, combination, and arrangement of parts, as will be described more fully hereinafter, illustrated in the drawings, and particularly pointed out in the appended claims.

The invention will be best understood by reference to the accompanying drawings, wherein:

Figure 1 is a side elevation of the wire twisting or connecting apparatus constructed in accordance with our invention, and

illustrating the same as applied to the strands to be connected;

Fig. 2 is a sectional view taken on line 2—2 of Fig. 1;

Fig. 3 is a view of one end of the device;

Fig. 4 is a sectional view taken on line 4—4 of Fig. 1 showing the supporting bar with the twisting supporting shank removed therefrom;

Fig. 5 is a fragmental sectional view taken through the twisting element;

Fig. 6 is an elevation of the rotatable member employed in forming the convolutions in the wire ends;

Fig. 7 is a sectional view taken substantially upon the line 7—7 of Fig. 1;

Fig. 8 is a similar view taken on line 8—8 of Fig. 1;

Fig. 9 is an end view of the lever member; and

Fig. 10 is a sectional view taken upon line 10—10 of Fig. 5.

In the present embodiment of the invention, there is shown a wire splicing or connecting apparatus which is designed as a hand operated tool adapted particularly for use by linemen, and while this embodiment is the preferred form of the device, it will be understood that the invention is not necessarily limited to this particular construction, as the principle involved may be put into practical application, through the instrumentality of various types of tools and machinery.

Referring now more particularly to the drawings, 15 indicates a wire clamping or holding device, the same comprising fixed and movable jaws 16 and 17 respectively, the said jaws being connected by a pivot pin 18, and providing co-operative clamping or gripping faces 19. The fixed jaw is extended beyond the pivot, providing a shank or arm 20, provided at its outer extremity with an opening 21 through which a bar 22 extends. A set screw 23 may be employed to secure the shank or arm 20 to the bar 22. The fixed and movable jaws 16 and 17 are forced into gripping engagement with each other by handles 24.

The bar 22 is preferably cylindrical in shape, and is provided with outwardly pro-

jecting longitudinally disposed keys 25, the said keys being placed together at their adjacent ends and being slightly out of alignment with each other. The extremities of 5 the bar 22 are provided with interiorly threaded sockets, within which the headed screw members 26 may be engaged. Arranged for sliding movement upon the bar 22 is a shank 27, the said shank being provided 10 at one end with an opening, as shown, through which the bar 22 extends, a key slot being provided in the lowermost portion of the said shank end to receive the keys 25 carried by the bar 22. This construction 15 enables the shank to freely slide longitudinally of the bar 22, but the key fitting in the key slot prevents rotary movement of the shank relative to the said bar. The opposite end of the shank 27 is provided with 20 a laterally disposed opening 28, a laterally disposed retracted slot 29 being provided in one side of the shank end and extending through the said end to communicate with the opening 28. The center of the opening 25 28 is alined with the gripping faces of the clamping member 15.

Mounted for rotation within the opening 28 and snugly engaging the annular walls thereof is a twisting member or barrel 30. 30 This barrel is provided at one end with an enlargement or head 31, the said head forming an annular shoulder upon the barrel to seat or rest against the side of the shank 27 adjacent the clamping element 15. The barrel is provided with a central opening 32, the latter being of relatively small diameter and extending throughout the length of the said barrel. A slot 33 is formed in one 35 side of the barrel, and is co-extensive with the opening 32. This slot is of substantially the same width as the slot 29 in the shank end, and is adapted to register therewith when the barrel is rotated. The end of the barrel opposite to that upon which 40 the head 31 is formed projects beyond the shank 27, and is provided inwardly from its extremity with an annular groove 34. An angular cut out portion 35 communicates with the channel 34 at one end and extends 45 inwardly and longitudinally of the barrel, providing stopping shoulders, the utility of which will be hereinafter more fully described. The peripheral face of the barrel 30 upon the opposite side of the groove 34 50 from which the cut out portion 35 extends is provided with a plurality of ratchet teeth 36. A barrel rotating handle or lever 37 is arranged upon the above described toothed end of the barrel. This lever is provided 55 with a head 38, having a laterally disposed opening 39 therein, a slot 40 being provided in the outer portion of the head and communicating with the opening 39 throughout the length of the latter. This slot is substantially 60 the same width as the slot 33 in

the barrel portion. A pawl 41 is rotatably mounted within a suitable opening 42 in the head 38, the said opening extending interiorly through one side of the head and communicating at its inner end with the 70 opening 39 therein. This pawl is normally held pressed inwardly or projecting into the opening 39 by a leaf spring 43, the latter being arranged upon the exterior of the head 38, and is turned or rolled, at its free 75 end, as at 44 to enable the same to be conveniently retracted by the finger. The pawl 41 is adapted to coöperate with the ratchet teeth 36 of the barrel, to play loosely over the said teeth when the handle 37 is rocked 80 in one direction but to create a positive connection between the handle and the barrel when the former is moved in the reverse direction. To maintain the head portion 38 of the rocker handle in proper position upon the barrel, a keeper 45 is extended through a suitable opening in the said head and projects at its inner extremity into the annular groove 34 in the barrel 30, a screw member 46 being employed to hold the keeper in 85 proper position. This arrangement enables the head 38 to rotate upon the barrel, and yet prevents the same head from moving laterally thereon.

A latch 47 extends through an opening 48 95 in the head 38 adjacent the pawl opening 42, the said latch being adapted to fit within the cut away portion 35 in the barrel 30, and to coöperate with the lateral shoulders thereon to prevent rotation of the barrel in 100 either direction. The outer extremity of the latch 47 is pivoted as at 49 to a finger lever 50 pivoted as at 51 to the handle 37 and normally maintained with the keeper projected inwardly by a leaf spring 52 arranged upon the handle. From this construction it is apparent that the latch 47 is normally pressed inwardly to engage with the annular shoulders formed by the cut 105 away portion 35 in the barrel, but when 110 pressure is applied to the outer extremity of the lever 50 by the thumb the said lever will rock upon its pivot 51 and will withdraw the latch 47 from engagement within the cut out portion 35. The cut out portion 115 35 in the barrel is so located, that when the latch 47 is engaged therein, the slot 40 upon the head 38 will be alined with the slot 33 in the barrel 30.

The outer face of the head 31 is provided 120 with projections, one side of each of which forms a shoulder 53, while the opposite edges provide cam faces 54.

In operation, there are twisting elements 125 of the above described character, arranged upon the bar 22 one on each side of the clamping member 15, with their shouldered heads 31 adjacent and in close proximity to the opposing faces of the said clamping member. The heads of the handles 37 are 130

locked through the latches 47 to the rotatable members or bars 30 by the shoulders limiting the cut out portions therein. The handles and barrel of each twisting element will 5 then move in unison and at the same time are rotated in such manner that the slots 33 in the barrels will align with the slots 29 in the ends of the shanks 27. One of the strands to be spliced or connected is then 10 engaged through the aligned slots in the openings 32 of one of the twisting elements extending throughout the length of the barrel 30. The strand is passed between the jaws of the clamping member 15 and is bent upwardly 15 at its extremity upon the remote face of the clamping member. The opposing strand end approaches the jaws from the opposite direction through the other twisting element and is passed between said jaws, 20 the extremity of said strand being bent at substantially right angles beyond the jaw and is engaged with one of the shoulders 53 of the head 31. With the shanks 27 moved upon the bar 22 in close proximity to the 25 clamping member, the latch retracting lever 50 of one twisting element is depressed, breaking the connection between the latch and the barrel, and the handle moved outwardly. The handle is moved back and 30 forth, and the ratchet connection between the same and the barrel moves the latter step-by-step in the direction to twist the wire end engaged by the shoulder 53 upon the opposite strand. As the wire end is 35 wound, the convolutions thereon lying close against each other force the head and shank 27 outwardly or away from the fixed clamping member. When the barrel has made a complete revolution in its wire twisting 40 movement, the latch 47 will seat within the cut out portion 38, and further rotary movement of the barrel, relative to the lever 37 will be prevented. The end of the wire protruding to the opposite side of the clamping 45 member 15 may in a like manner be twisted by operating the rotating or twisting device and lever on the opposite end of the bar without removing the instrument from its original position or changing 50 the tool in any way. To enable the central openings in the barrel 30 to properly align with the wire ends projecting through the clamping jaws and lying in close proximity to each other, the keys 25 carried by the bar 55 22 are slightly disaligned, the said keys being so arranged as to properly position the barrel openings for engagement with the different wire extremities.

By the arrangement of the cam faces approaching the shoulders 53 on the heads 31, it is obvious that the operating handle of each twisting device may be locked to the rotatable barrel and the twisting operation performed by oscillating the barrel. The 60 ability of the barrels to make complete revo-

lutions enables the device to efficiently twist the wire ends inclosed with a sleeve, the said sleeve being twisted together with the wire inclosed thereby. After the barrel has made a complete revolution the slot therein 70 aligns or registers with the corresponding slots in the shank and handle end, whereby the device may be readily disengaged from the twisted sleeve and wire ends.

When it is desired to twist together the 75 extremities of wires coming from the same direction, the ends of the wires are clamped between the jaws 15, and their extremities bent laterally in opposite direction to be engaged by the spaced shoulders upon one of 80 the barrel heads 31. Rotary movement of the barrel will then twist together these ends and firmly bind the same upon each other.

It is apparent from this disclosure that a 85 simple and efficient means is provided for the purpose of connecting wire ends. The wire terminals can be quickly and tightly spliced or twisted together by the use of the instrument, and with an expenditure of but little energy. While the present invention 90 is described as a manually operated tool, it is apparent that the principle involved is capable of being practically carried forth in other forms of devices or machines, and therefore the invention is not to be limited 95 to the particular construction set forth. It is also obvious that various changes in the minor details of construction may be resorted to without departing from the spirit of the invention or exceeding the scope of 100 the claims.

What is claimed is:—

1. In a wire twisting device, a bar having keys thereon, a clamping member fixed to and depending from said bar, a shank 105 mounted for sliding movement upon the bar and being provided with a notch to receive said keys, a rotatable member carried by said shank and having a central portion aligned with the gripping faces of said 110 clamping member, the said rotatable member being provided with a slot communicating with said opening, the said shank being provided with a slot communicating with the said rotatable member, a lever rotatably 115 mounted upon said rotatable member, the said lever being provided with a slot communicating with said rotatable member, a locking connection between said lever and rotatable member, a pawl and ratchet connection between said members, shoulders on 120 said rotatable member adjacent said clamping member, and means for releasing said locking connection, substantially as described.

2. In a wire twisting device, a bar, a clamping member depending from said bar, a pair of shanks slidably mounted on said bar and one being disposed upon each side of said clamping member, a rotatable mem- 130

ber carried by each shank and each having a central portion alined with the gripping faces of said clamping member, the said shanks and their respective rotatable members having slots therein adapted to be brought into registration, a lever rotatably mounted upon each rotatable member, the said levers having slots adapted to aline with the slots in their respective rotatable members, means for establishing a power connection between said levers and their ro-

tatable members, and wire holding shoulders on each of said rotatable members, substantially as described.

In testimony whereof we affix our signatures in presence of two witnesses.
